UNITED STATES PATENT OFFICE.

WILLIAM BENNINGTON AND JACOB GUNZENHAUSER, OF CHICAGO, ILLINOIS.

PORTABLE MILLING-TOOL.

1,055,013.

Specification of Letters Patent. Patented Mar. 4, 1913.

Specification filed March 23, 1912. Serial No. 685,856.

To all whom it may concern:

Be it known that we, WILLIAM BENNINGTON and JACOB GUNZENHAUSER, citizens of the United States, and residents of the city 5 of Chicago, county of Cook, and State of Illinois, have invented certain new and useful Improvements in Portable Milling-Tools, of which the following is a specification.

10 Our invention relates to portable milling tools and more specifically to a device of this character designed especially for use in dressing rivet heads.

The object of our invention is the production of a device of the character mentioned which will be of durable and economical construction, one which it will be safe to manipulate, and one which will be of high efficiency in use.

20 Other objects will appear hereinafter.

With these objects in view, our invention consists in the combinations and arrangements of parts hereinafter described and claimed.

25 Our invention will be more readily understood by reference to the accompanying drawings forming a part of this specification, and in which—

Figure 1 is a side elevation of a milling tool embodying our invention, Fig. 2 is a 30 bottom plan view of the tool, Fig. 3 is a transverse section taken on line *u u* of Fig. 2, Fig. 4 is a transverse section taken on line *v v* of Fig. 5, Fig. 5 is a longitudinal section taken on substantially line *w w* of Fig. 1, Fig. 6 is a sectional end view of the 35 tool, Figs. 7, 8 and 9 are transverse sections taken on lines *x x*, *y y* and *z z*, respectively, of Fig. 5, and Fig. 10 is a plan view of one 40 of the cutters which are used in the tool.

The preferred form of construction, as 45 illustrated in the drawings, comprises a substantially cylindrical body 1 which is mounted upon a shank 2, the tapering inner end of said shank removably engaging a tapering socket 3 formed for the reception thereof in one end of said body. A transversely extending opening 4 is provided in the body 1, which intersects with 50 the bottom of socket 3, into which a key or other suitable tapering tool may be inserted for effecting ready forcing of the shank 2 to disengagement, as will be readily understood. The outer end of the shank 2 is of

the usual tapering form for insertion into 55 any conventional holder which may be used in conjunction with the tool.

The opposite end of the body 1 is provided with a head 5 in which is formed a plurality of equally spaced sockets 6 which open in the end of said body. The sockets 6 are designed for engagement by shanks 7 of the cutters 8 which are arranged as clearly shown in Figs. 5 and 6, so that, when the body 1 is properly rotated, the cutting 65 edges 8' of said cutters will be adapted to operate upon any surface into which the same are brought into contact to effect dressing thereof. Said edges 8' are preferably of the form shown, in order to adapt 70 the same for use in dressing or trimming the head of a rivet. The heads of the cutters 8 engage substantially radially disposed recesses 9 provided in the head 5 which serves to positively hold the same 75 against relative rotary movement, said cutters being locked in position against longitudinal movement by means of set screws 10 which are threaded in the head 5, as clearly shown in Fig. 6; the periphery of 80 said head being cut away at 10' for the accommodation of said screws.

The body 1 is rotatably mounted in a sleeve 11, longitudinal movement of said body in said sleeve being prevented by the 85 stationary collar 12 which is formed adjacent the forward end of said body and a removable collar 13 which is secured by screws 14 to the opposite end of said body, a fiber ring 15 being preferably interposed 90 between the adjacent edges of the collar 13 and the sleeve 11 to alleviate friction. Also, the central portion of the body 1 is reduced in order to reduce the surface of the body 1 which is engaged by the sleeve 11 and thereby lessen the friction between said members.

Threaded upon the sleeve 11 is a ring 16 upon which are equally spaced outwardly projecting posts 17, as clearly shown in Fig. 100 9. Inclosing the outer end portion of the body 1 is a sleeve 18, the rearward end of which is secured by means of screws 19 to the posts 17. The sleeve 18 serves as a gage for the cutters 8, limiting or gaging the 105 depth of the cut which may be taken by said cutters, it being clear that, when in operation, the cutters will be permitted to cut into

the work operated upon until the outer end of the member 18 contacts the surface of the work, when the cutting operation will cease. This being so, it will be seen that adjustment of the depth of the cut by the cutters will be effected by longitudinally adjusting the position of the member 18 relative to said cutters and hence relative to the sleeve 11 which is fixed against longitudinal movement relative to said cutters. Adjustment of the member 18, as above referred to, is effected by rotating the sleeve 11 relative to the member 16 and hence said member 18, it being clear that upon rotation of the member 11, the member 16 and hence the member 18, by virtue of the threaded connection between the members 11 and 16, will be moved longitudinally. One end of the member 11 is formed with radially extending perforations 20 into which the point of a tool may be inserted for effecting this rotation of the member 11. The member 16 and hence the member 18 are locked in positions of adjustment relative to the member 11 by means of a lock-nut 21 which is threaded upon the latter for engagement with one extremity of the member 16. The nut 21 is provided with recesses 22 into which the point of a tool may be inserted for effecting this rotation thereof. With the arrangement set forth, it will be seen that upon the member 16 having been adjusted upon the member 11, the nut 21 will be moved into engagement with the former to securely lock the same in the desired position. The member 18 is formed with openings 23 through which the cutters and the work operated upon may be viewed when the tool is in operation, said openings also affording access to the heads of screws 10 for adjusting the cutters 8. The member 18 in addition to serving as a gage, as above set forth, also serves in the capacity of a guard, it being clear, that said member, as arranged, will be adapted to prevent the fingers or hand of the operator contacting with the blades during operation of the device.

Interposed between the sleeves 11 and 18 is a third sleeve 24 in which the body 1 is rotatably mounted, the latter being locked against longitudinal movement in said sleeve by reason of the forward extremity of said sleeve engaging the head 5 and the opposite extremity of said sleeve engaging a shoulder 13' formed upon the collar 13. The sleeve 24 is formed with longitudinally extending elongated slots 25 to provide clearance for the posts 17 of the gage carrier 16, and a substantially rectangular slot 26 is provided in the sleeve 24 to afford access to the lock-nut 21 in rotatably adjusting the same. The rearward end of the sleeve 24 is formed with a slot 27 which is adapted for registration with the heads of screws 14 in order to gain access to the latter for attaching or detach-

ing the collar 13, and the opposite end of said sleeve is formed with an oil hole 28 for lubricating purposes.

In using the tool, the outer end of the shank 2 is secured in the holder in conjunction with which the tool is used, the power shaft which is connected with the holder being preferably of the flexible type so as to permit of free manipulation of the tool. The sleeves 18 and 24 are then engaged by one or both hands, said sleeves thus constituting a grip whereby the tool may be pressed into engagement with the work which it is desired to dress. Since the members 18 and 24 serve in the capacity of a grip, the outer surfaces thereof are knurled so as to prevent slipping.

A tool of the construction set forth is simple and economical, hence may be manufactured at a low cost, the same may be readily manipulated to effect the expeditious dressing of bolt heads or the like, and the construction is such as to not be susceptible to readily becoming inoperative. The cutters 8 are removable so that cutters of different sizes may be used if desired.

While we have illustrated and described the preferred form of construction for carrying our invention into effect, this is capable of variation and modification without departing from the spirit of the invention. We, therefore, do not wish to be limited to the exact details of construction set forth, but desire to avail ourselves of such variations and modifications as come within the scope of the appended claims.

Having described our invention, what we claim as new and desire to secure by Letters Patent, is:

1. A tool of the character described comprising a substantially cylindrical body; a plurality of cutters arranged at one end of said body; a sleeve in which said body is rotatably mounted; means for holding said body against longitudinal movement in said sleeve; means connected with and longitudinally adjustable upon said sleeve for gaging the depth of the cut of said cutters; and rotatable manually adjustable means for securing said gaging means in positions of longitudinal adjustment relative to said sleeve, substantially as described.

2. A tool of the character described comprising a substantially cylindrical body; a plurality of cutters arranged at one end of said body; a sleeve in which said body is rotatably mounted; means for holding said body against longitudinal movement in said sleeve; means connected with and longitudinally adjustable upon said sleeve for gaging the depth of the cut of said cutters; and a nut threaded upon said sleeve for locking said gaging means in positions of longitudinal adjustment relative to said sleeve, substantially as described.

3. A tool of the character described comprising a substantially cylindrical body; a plurality of cutters arranged at one end of said body; a sleeve constituting a grip in which said body is rotatably mounted; means for holding said body against longitudinal movement in said sleeve; means in threaded connection with said sleeve for longitudinal adjustment relative thereto for gaging the depth of the cut of said cutters; and means for locking said gaging means in positions of longitudinal adjustment upon said sleeve, substantially as described.
4. A tool of the character described comprising a substantially cylindrical body; a plurality of cutters arranged at one end of said body; a sleeve constituting a grip in which said body is rotatably mounted; means for holding said body against longitudinal movement in said sleeve; means in threaded connection with said sleeve for longitudinal adjustment relative thereto for gaging the depth of the cut of said cutters; and a lock-nut for locking said gaging means in positions of longitudinal adjustment upon said sleeve, substantially as described.
5. A tool of the character described comprising a substantially cylindrical body; a plurality of cutters arranged at one end of said body; a sleeve in which said body is rotatably mounted; means for holding said body against longitudinal movement in said sleeve; a second sleeve connected with said first mentioned sleeve and in threaded connection therewith for effecting longitudinal adjustment thereof to gage the depth of the cut of said cutters; and a lock-nut threaded upon said first mentioned sleeve for locking said gaging sleeve in positions of longitudinal adjustment upon said first mentioned sleeve, substantially as described.
6. A tool of the character described comprising a substantially cylindrical body having a head at one end; a plurality of cutters removably secured in said head; a sleeve constituting a grip in which said body is rotatably mounted; means for holding said body against longitudinal movement in said sleeve; and non-rotatable means connected with and longitudinally adjustable relative to said sleeve for gaging the depth of the cut of said cutters, substantially as described.
7. A tool of the character described comprising a substantially cylindrical body having a head at one end containing a plurality of sockets; a plurality of cutters having their shanks engaging said sockets; means for removably securing said cutters in position in said sockets; a sleeve constituting a grip in which said body is rotatably mounted; means for holding said body against longitudinal movement in said sleeve; and means connected with and longitudinally adjustable upon said sleeve for gaging the depth of the cut of said cutters, substantially as described.
8. A tool of the character described comprising a substantially cylindrical body; a plurality of cutters arranged at one end of said body; a sleeve in which said body is rotatably mounted; means for holding said body against longitudinal movement in said sleeve; a second sleeve encircling said first mentioned sleeve for gaging the depth of the cut of said cutters; means carrying said second mentioned sleeve and in screw-threaded connection with said first mentioned sleeve whereby rotation of said means upon said first mentioned sleeve effects longitudinal adjustment of said second mentioned sleeve upon said first mentioned sleeve; means for locking said second mentioned sleeve in positions of adjustment relative to said first mentioned sleeve; and a third sleeve interposed between said before mentioned sleeves and in which said body is rotatably mounted and held against longitudinal movement, substantially as described.
9. A tool of the character described comprising a substantially cylindrical body; a shank engaging a tapering socket provided in one end of said body, there being a transversely extending opening in said body intersecting said socket for the insertion of a key in effecting detachment of said shank; a plurality of cutters arranged at the other end of said body; and means constituting a grip substantially completely inclosing said body and in which the latter is rotatably mounted and held against longitudinal movement, substantially as described.
- In testimony whereof we have signed our names to this specification in the presence of two subscribing witnesses.
